United States Patent

Des. 241,003
Patented Aug. 17, 1976

241,003

DOOR CLOSER BODY

Edward Herman Meisner, Wyckoff, N.J., assignor to Eaton Corporation

Filed Oct. 29, 1974, Ser. No. 518,919

Term of patent 14 years

Int. Cl. D8—09

U.S. Cl. D8—203

FIG. 3

FIG. 4

FIG. 5

FIG. 1 is a front view of a door closer body showing my new design;

FIG. 2 is a top view of the door closer body of FIG. 1;

FIG. 3 is a bottom view of the door closer body of FIG. 1;

FIG. 4 is a side view taken from the right side of FIG. 1; and

FIG. 5 is a side view taken from the left side of FIG. 1.

I claim:

The ornamental design for a door closer body, substantially as shown.
